UNITED STATES PATENT OFFICE.

RICHARD P. ELLIOTT, OF BOSTON, MASSACHUSETTS.

DESIGN FOR A FURNITURE-STANDARD.

SPECIFICATION forming part of Design No. 33,865, dated January 8, 1901.

Application filed December 13, 1900. Serial No. 39,787. Term of patent 14 years.

To all whom it may concern:

Be it known that I, RICHARD P. ELLIOTT, a citizen of the United States, residing at Boston, in the county of Suffolk and State of Massachusetts, have invented and produced a new and original Design for a Furniture-Standard, of which the following is a specification, reference being had to the accompanying drawing, forming, forming part thereof.

The figure is a side elevation of a furniture-standard, showing my new design.

As shown in the drawing, the leading or material feature of my design consists of the upper straight portion *a*, projecting from which is the bracket-shaped portion *b*. At its lower extremity the straight portion *a* becomes tangent to the inwardly-curved portion *c*, which becomes tangent at its lower extremity to the

outwardly-curved portion *d*. Tangent to the upper extremity of the inwardly-curved portion *e* is the straight portion *f*, projecting from which is the bracket-shaped portion *g*. Tangent to the lower extremity of the inwardly-curved portion *e* is the outwardly-curved portion *h*.

Having described my invention, what I claim as new, and desire to secure by Letters Patent, is—

The design for a furniture-standard as herein shown and described.

Dated at Boston, Massachusetts, this 10th day of December, 1900.

RICHARD P. ELLIOTT.
